WAVE GUIDE VARIABLE ATTENUATOR

Shepard Roberts, Cambridge, Mass., assignor, by
mesne assignments, to the United States of
America as represented by the Secretary of War

Application February 25, 1944, Serial No. 523,885

7 Claims. (Cl. 333—81)

1

This invention relates to a guide control and particularly to a variable attenuator for use in wave guides.

The principal object of the invention is to provide a simple, inexpensive and readily adjustable attenuator of this character wherein there is little or no reflection of the guided waves.

In the accompanying drawing, Fig. 1 is a partly cut-away perspective view of the invention, and Fig. 2 is a modification.

The attenuator is shown as embodied in a rectangular metallic wave guide portion 5, Fig. 1, which is constructed in the usual manner and with the usual ratio of larger side to shorter side and dimensions determined by transmitted frequency. If desired, the attenuator may be applied to a circular wave guide having a mode of wave propagation where the maximum intensity electric vector lies in a diametral plane. An elongated strip of resistance material 6 is disposed within the guide portion, end 7 of said strip being fixed to a shorter guide side by fastening means such as bolt 8. Thus the anchored end is at a region of said guide where the electric vector has its minimum intensity. Strip 6 may be composed of some insulating material such as Bakelite with one side thereof coated with a layer of carbonaceous material to provide a desired resistance characteristic. The free end of the strip is tapered as shown at 9, the longitudinal length of the taper being at least a half wave length of the transmitted wave.

A micrometer or similar adjusting device 10 is fixed to the exterior of the wave guide portion and positioned in relation to the free end of strip 6. The guide portion is suitably apertured to receive positioning pin 11 of the micrometer. This pin bears on the surface of strip 6 near its free end and causes said strip to bend away from the guide side into the space within the guide in accordance with micrometer adjustment. The pin is preferably of small diameter and may be of insulating material. A recovery spring 15 of insulating material such as a rubber band extends between strip 6 near its free end and a stationary support 16, which may be on the micrometer.

The two surface dimensions of resistance strip 6 may be varied, although the small transverse dimension or width is generally slightly less than the width of the shorter guide side. This small dimension of strip 6 always lies parallel to the maximum intensity electric vector, this generally being in a plane normal to the larger guide side. Similarly in the case of a circular guide, the

2

small strip dimension is parallel to the plane of the maximum intensity electric vector.

Attenuation is obtained by positioning the resistance strip within the guide space so that the movable part constitutes an effective portion which may be moved from a position of minimum electric field intensity (right up against the guide wall) to a position of maximum field intensity (substantially in the center of the space enclosed by the guide walls). The micrometer provides visual indication of strip position, although a simple screw control or other means may be used if desired.

The modification of Fig. 2 shows an attenuator embodied in a rectangular wave guide portion 20 constructed and dimensioned in the usual manner. A narrow centrally disposed longitudinal aperture 21 is provided in the larger guide side. This aperture is along the line of intersection of the wave guide wall and plane of maximum electric field intensity. A circular guide may have a similar construction. The attenuator comprises an elongated supporting metallic member 22, which is suitably connected to the apertured guide side as by hinge 23. A thin sheet of resistance material 24 depends from supporting member 22 and registers with aperture 21. The resistance sheet is wide at its central region and tapers or curves at least half a wave length to each end as shown. The center width of sheet 24 substantially corresponds to the width of a shorter guide side so that the element may terminate just short of its opposite guide side when moved to its maximum position within the guide. Elements of hinge 23 may fit rather tightly so that friction will retain the pivoted attenuator in any predetermined position.

It will be seen that the invention provides a readily variable attenuator for use with wave guides. The device has been found to cause little or no appreciable wave reflection. Having thus described the invention, what I claim as new and desire to secure by Letters Patent is:

1. An attenuator for use in a wave guide in which high frequency electric waves are propagated comprising a wave guide portion having a mode of propagation in which the maximum intensity electric vector lies in a flat plane symmetrically through and longitudinal of said guide portion, a thin, flat resistance member carried by said guide at a region where the electric vector is substantially zero, and lying generally in a plane parallel to that of the maximum intensity electric vector, and means for moving at least part of said member in a direction generally perpendicular to the maximum intensity electric

vector from a region of minimum field intensity to a region of maximum field intensity.

2. The structure of claim 1 wherein said member has a tapered end along the line of wave propagation with the taper portion at least half a wave length in the full attenuation position.

3. An attenuator for use in a wave guide in which high frequency electric waves are propagated comprising a wave guide portion having a mode of propagation in which the maximum intensity electric vector lies in a flat plane symmetrically through and longitudinal of said guide portion, a thin, flat resistance member mounted on said guide to lie in the maximum intensity electric vector plane, said guide being slotted to clear said member and means for moving said member from the exterior of said guide to the interior thereof for varying the attenuation, wherein said member is pivotally mounted at one end thereof with the member having the general shape of a segment of a circle.

4. In combination, a hollow wave guide, means to vary the intensity of waves transmitted therethrough, said means comprising a flexible dielectric member attached to the inner wall of said guide, and means arranged externally of said guide and connected with said member through a wall of said guide variably to adjust said member in positions extending from the wall of said guide toward the center thereof gradually along the length of a portion of the guide, said dielectric member carrying thereon resistance material to absorb the energy of said wave.

5. In combination, a dielectric wave guide along which a high frequency wave is propagated comprising a hollow rectangular pipe having walls of conductive material and attenuating means for said wave comprising, a thin strip of resistive material extending longitudinally along the inner surface of one of said walls, said strip having its end presented to a wave traveling

through said guide supported adjacent the inner surface of said one wall and means to move said strip toward the center of said guide in a direction normal to its length, whereby the impedance of said guide varies gradually through said attenuating means in the direction of propagation of said wave.

6. In a high frequency system, a hollow tubular guide for an electro-magnetic wave, said guide having a conductive inner surface, and an elongated strip having a conductive surface layer on at least one side thereof with a resistance substantially greater than that of said guide surface, said strip being positioned within said guide and extending lengthwise thereof with said side substantially parallel to the electric field of said wave, a point on said strip being secured to a wall of said guide with the strip extending away from said point in angular relation to said wall.

7. In a high frequency system, a hollow tubular guide for an electro-magnetic wave, said guide having a conductive inner surface and a rectangular transverse section with a pair of wide walls and a pair of narrow walls, and an elongated strip having a conductive surface layer on at least one side thereon with a resistance substantially greater than that of said guide surface, said strip being positioned within said guide and extending lengthwise thereof with said side substantially perpendicular to said wide walls, a point on said strip being secured to one of said narrow walls with the strip extending away from said point in angular relation to said one narrow wall.
